UNITED STATES PATENT OFFICE.

AUGUSTUS M. HENRY, OF BROOKLYN, NEW YORK, ASSIGNOR TO WILLIAM W. WEITLING, TRUSTEE, OF COLLEGE POINT, NEW YORK.

ROTARY CASTING.

Application filed February 2, 1924. Serial No. 690,289.

This invention relates to improvements in rotary casting, and has particular reference to a method and apparatus for casting car wheels and like articles made of ferrous metals; the invention having, broadly, particular pertinence and value so far as substantially disk-like or cup-like articles, rather than ring-like or sleeve-like articles, are concerned.

As to car wheels particularly, special problems are presented in rotary casting, since according to present practice a small hole is presented as compared to the bulk of material surrounding said hole (keeping in mind especially the thickness of the casting between the edge of the hole and the periphery of the wheel). This is especially true where molds are employed in the casting process of metal or having linings other than the ordinary foundry sand and such linings are quicker heat-absorptive types than the ordinary foundry sand.

These problems have to do particularly with controlling the distributor or feeding means for the molten metal, or the mold, or both, in such a manner that in making unitary, integral or single-cast ferrous metal castings of the kind above mentioned, it is possible to produce the same rapidly and economically and, at the same time, preclude the possibility of the metal congealing in distinct layers or arcuate or annular striations, commonly known as "cold-shots".

Accordingly, the present invention provides an improved apparatus and method for accomplishing the above purposes wherein a charge of molten metal is injected into the mold at a high velocity and as it is being fed into the mold cavity the spout through which the metal flows is rotated.

It is further proposed to pour the metal into the mold by a rotation of the feeding spout so that the metal will be delivered tangentially with respect to the peripheral plane of the mold cavity and to simultaneously heat the mold to obviate the possibility of the metal becoming chilled during the casting operation.

A further object is to provide a mold in which the congelation of the molten metal is graduated and controlled radially with respect to the center of the casting by an application of a varying degree of heat control to the walls of the mold cavity.

The above and other objects will appear more clearly from the following detailed description when taken in connection with the accompanying drawings, which illustrate preferred embodiments of the inventive idea.

In the drawings—

Figure 1 is a side elevation, partly in section, of an apparatus constructed in accordance with the invention;

Figure 2 is a sectional view, on an enlarged scale, through one form of mold employed;

Figure 3 is a section taken on line 3—3—3 of Figure 2;

Figure 4 is a view similar to Figure 2 showing a different form of mold; and

Figure 5 is a section taken on line 5—5—5 of Figure 4.

The apparatus shown in Figure 1 includes a container 5 having a lining 6 of suitable heat-resisting material.

Molten metal 7 is poured into the container 5 preparatory to charges thereof being ejected therefrom to the mold by an apparatus which preferably includes a plunger 8 supported by a sliding block 9 movable in guides 10 formed in the bottom of the lining 6.

Extended into the container 5 is a lever 12, pivoted intermediate its ends at 13 and having a slotted connection 11 with the sliding block 9, so that as the lever 12 is actuated about its pivot a longitudinal movement of the sliding block and plunger 8 with respect to the bottom of the container will be effected. The upper end of the lever 12 has connected thereto at 15 a plunger rod 14 which extends into a mechanism conventionally illustrated at 34, which may be hydraulically or otherwise operated to quickly and forcibly eject the plunger rod 14 from the mechanism in such manner as to impart a rocking movement to the lever 12.

Normally the effective end of the plunger 8 closes the inner enlarged end 16 of the inner section 17 of the delivery tube so as to prevent the molten metal from flowing into said tube. However, when a charge is to be ejected from the container 5 the mechanism 34 first operates to retract the rod 14 slightly into the mechanism to move the plunger to the left, as shown in Figure 1. A charge of the metal 7 then flows into the end 16 of the inner section, whereupon the

sliding block and plunger 8 are moved to the right to force the charge through the inner section 17. By reason of the action of the mechanism above described the complete charge of molten metal will be forced through the delivery tube at an exceedingly high velocity.

The delivery tube further includes an outer section 18 surrounding the inner section 17 in spaced relation thereto to form a non-heat-conducting air space between the sections. The inner section 17 is provided at intervals with projections 19 which are designed to prevent sagging of the inner section due to the excessive heat applied thereto by the molten metal passing through the same. The outer or delivery ends of the sections 17 and 18 are bent downwardly at an angle of approximately 45°; and arranged in longitudinal alignment with the inner section 17 is the delivery spout 20.

Referring now to Figs. 2 and 3, spout 20 has its discharge end bent laterally at substantially right angles to the longitudinal axis of said spout.

The inlet end 21 of the spout is flared to receive the adjacent end of the inner section 17 so that the metal from said section will readily flow into the spout.

30 The spout 20 is supported in rings 22 arranged in spaced relation in a rotatable sleeve 23, one end of which sleeve is secured to a suitable bearing 24 revoluble about the outer section 18 of the delivery tube. A suitable gear 33 is secured to the sleeve 23 intermediate the ends thereof and is connected to a suitable mechanism (not shown) utilized to impart high-speed rotary movement to the sleeve 23 whereby a 35 similar movement of the spout 20 is produced.

40 The permanent mold shown in Figure 2, wherein a cast car-wheel is indicated at C, includes the complementary sections 25 and 45 26, preferably constructed mainly of nichrome and provided therein with opposed recesses 25^a and 26^a, respectively.

45 Embedded in each section of the mold contiguous to the molding cavity therein is a layer 35 of a heat-insulative and electrically non-conductive material, such as alundum paste or cement, and in each layer 50 35 there is placed a resistance wire 36 formed in a continuous spiral, the convolutions of which are spaced and insulated from the metal portions of the mold by the layer 55 35. The wires 36 of the two sections of the mold combine to practically surround the cavity formed by the recesses in said sections and have their leads V and V' 60 extended through the sections and connected to the contact rings 27 and 27', respectively.

65 Referring to Figure 1, the sections of the mold are held together by threaded rods 28 which are actuated in a manner fully dis-

closed in U. S. Letters Patent to me No. 1,501,338, to maintain the sections of the mold in cooperative relation and permit the section 26 to be moved relative to the section 25 whenever desired. The section 25 of the mold has a shaft 30 connected thereto, which shaft may be driven by an electric motor or any other convenient means conventionally illustrated at 37.

Again examining Figures 2 and 3, the axis of rotation of the shaft 30 and that of the spout 20 are coincident so that as the mold and spout are rotated the molten metal from the spout will be delivered and evenly distributed into the cavity in the mold. The spout and mold are rotated in the same direction and, in accordance with the present invention as preferably carried out, the spout is driven at a speed very, very slightly decreased with respect to that of the mold so that the metal from the spout will be tangentially delivered into the mold cavity but so that the entire charge of metal will be delivered to the mold during about one revolution thereof.

90 In the form of mold shown in Figures 4 and 5, the two mold sections thereof are so constructed as to permit of variable cooling effects and produce a radially graduated congelation control. For this purpose the centers of the sections of the mold have mounted therein the carbon blocks 38 and 39, incidentally utilized to case-harden the hub portion of the casting C. As in the construction shown in Figure 2, each mold section includes a metal member; but in Figure 4 said members marked 25^b and 26^b are shaped to permit employment of carbon mold members 38 and 39. Also, as in Figure 2, a resistance coil 40 is embedded in an insulating bed 41 in each section of the mold and the plane of each coil and bed is arranged diagonally with respect to the center plane of the mold cavity with the convolutions of the coils positioned nearest to the cavity at points contiguous to the hub portion of the casting. In this manner a graduated heat will be applied to the molten metal as it is being cast, in such a way that the outer portion of the casting C will be chilled, and such chill will gradually disappear toward the hub of the car-wheel. Desirably, for obtaining greater strength throughout the entire wheel, the peripheries of the carbon blocks 38 and 39 are corrugated and the convolutions of the resistance wires 40 are also corrugated, as indicated in Figure 4.

110 I claim:

1. The method of casting which consists in rotating a mold, injecting a charge of molten metal therewith, and heating said mold in different degrees in different parts.
2. The method of casting which consists in rotating a mold, injecting a charge of

molten metal thereinto, and heating said mold in different degrees at different radially related parts.

3. The method of casting which consists in rotating a mould, injecting a charge of molten metal thereinto, and modifying the temperature of said mold, by means other than the molten metal, simultaneously in different degrees at various points different distances from the axis of rotation of the mould.

4. The method of casting which consists in rotating a mold, injecting a charge of

molten metal thereinto, and heating said mold in different degrees at different circumferentially related parts.

5. The method of casting which consists in rotating a mould, injecting a charge of molten metal thereinto, and modifying the temperature of said mold, by means other than the molten metal, simultaneously in different degrees at various points around the mould axis, that is, circumferentially of the mould.

AUGUSTUS M. HENRY.
